STAPLING HAMMER

Roy E. Peterson, Norwalk, Conn., assignor, by
mesne assignments, to The E. H. Hotchkiss
Company, Norwalk, Conn., a corporation of
Delaware

Application March 21, 1947, Serial No. 736,194

8 Claims. (Cl. 1-49)

This invention relates to a staple driving machine, particularly of the type known as a hammer type tacker, in which the staple is driven by using the device in the manner of a hammer and swinging it to strike a blow with the head portion of the device. In prior constructions of this type of device it has been common to use a weight or hammer element which, when movement of the device was arrested as it struck the surface of the material, acted as a hammer to operate the staple driving mechanism and impart a blow to the staple for the driving operation. This required a construction of considerable weight which, if used for a considerable time, soon was very fatiguing to the operator, and also the blow of the heavy construction was apt to mar or injure the work being operated on.

It is, therefore, an object of the present invention to provide a simplified and much lighter construction so that it is less tiring to the operator and less apt to mar or injure the work, and one in which the operation is more nearly like that, or no more fatiguing than, the operation of an ordinary hammer.

It is also an object to provide a construction in which shifting of the striking element is relied on to drive the staple rather than the inertia of a relatively heavy or hammer element, as in prior constructions.

Another object is to provide an improved lock 130 for the follower or staple feed mechanism which cannot be accidentally unlocked and cause release of the follower and failure of the feed mechanism to operate.

With the foregoing and other objects in view, I have devised the construction illustrated in the accompanying drawings forming a part of this specification. It is, however, to be understood the invention is not limited to the specific details of construction and arrangement shown, but may embody various changes and modifications within the scope of the invention.

In these drawings:

Fig. 1 is a longitudinal section of the device showing the parts in the normal position ready for use in driving the staple, the section being substantially on line 1—1 of Fig. 3, but showing the staple strip and follower in elevation;

Fig. 2 is a similar view of the forward end thereof showing the parts in their positions at the end of the staple driving operation:

Fig. 3 is a transverse section just under the top wall of the head or housing, taken substantially on line 3-3 of Fig. 1.

Fig. 4 is a vertical section in substantially the

plane of the front face of the striking element and on substantially line 4-4 of Fig. 1;

Fig. 5 is a similar section with the striking element removed and taken substantially on the plane of the front surface of the driver, the section being substantially in the plane of the line 5-5 of Fig. 1.

Fig. 6 is a transverse section substantially on the line 6-6 of Fig. 1;

10 Fig. 7 is a longitudinal horizontal section of the rear end portion of the handle taken substantially on line 1—1 of Fig. 8;

Fig. 8 is a rear end view of the handle;

15 Fig. 9 is a front view of the device with the head or housing, the striker and driver removed, and looking from the left of Fig. 10;

Fig. 10 is a side view of the end portion of the device with the head or housing, striker and driver removed, as in Fig. 9;

20 Figs. 11, 12 and 13, are a side, rear and bottom view respectively of the striker element;

Figs. 14 and 15 are an edge and front view respectively of the driver;

Fig. 16 is a perspective view of the carrier for the driver, and Figs. 17 and 18 are a front and side view respectively of the intermediate driving gear and the mounting therefor.

The device comprises a handle portion 1 and a head portion 2 at the forward end of the handle portion. The handle structure includes a longitudinal staple feed or guide bar 3, preferably of substantially U-shaped section, as shown in Fig. 6, along which a strip of staples 4 may be fed to 35 the staple driving position, these staples being of substantially inverted U shape, and being fed along the guide bar 3 by a suitable follower 5 which is also of inverted U shape to substantially fit the guide bar 3. The side walls 6 of the bar 40 are preferably inclined upwardly and outwardly, as shown in Fig. 6, and the prongs of the staples and the side walls 7 of the follower are preferably inclined inwardly in a similar manner, so that these inclined side walls 6 cooperate to retain 45 the staples and the follower in the proper position on the guide bar 3 and prevent them from moving upwardly off this bar during handling or operation of the device. A guide or retaining

operation of the device. A guide or retaining bar 3 is mounted above the bar 3 to extend longitudinally thereof and spaced a suitable distance above the bar 3 to give clearance for movement of the staple strip and the feed follower 5 and to also assist in retaining them on the bar 3. This bar is preferably of sheet metal formed to substantially U shape as shown in Fig. 6. Both the

bars 3 and 8 are mounted in a substantially U-shaped longitudinal housing bar 9, the bar 3 being mounted on the bottom wall of this housing and the bar 8 being mounted between the side walls 10 at the upper ends thereof and secured by any suitable means, such as welding or transverse pins or rivets 11. The bar 3 may also be secured by any suitable means, such as welding, rivets or screws 12.

The follower 5 is fed along the bar 3 to advance the staples to the driving position by means of coil spring 13 on a rod 14 slidably connected at its inner end to the follower 5 by any suitable means, such as the loop 15 embracing the rod and secured to the top wall of the follower. The rod may have an enlarged head 16 to prevent the follower being forced off the rod by the spring. At its outer end the rod is mounted on a block 17 which may be bent up from a strip of metal of suitable gauge to provide a vertical end wall 18 to which the end of the rod is secured, and an upwardly and forwardly inclined portion 19 provided with an elongated opening 20 (Fig. 7) to cooperate with the forwardly extending hooked lug 21 of a pivoted catch 22, pivoted in the bar 8 at 23 and normally held in its lower or holding position by a spring 24. This hook provides a notch opening at its forward side toward the front. At its rear or outer end it is provided with an upwardly extending thumb piece 25 for releasing the catch, and this may be knurled or roughened as indicated at 26 if desired to facilitate operation. Due to the fact the spring 13 tends to shift the block 17 rearwardly and the hook 21 of the catch extends under and forwardly of the bar 27 (Fig. 7) of the member 19, it will be seen that the only way this hook can be released is to first shift the block 17 forwardly against the action of the spring 13. Therefore there is no danger of this catch being inadvertently or accidentally released to release the staple feeding mechanism during operation of the device. The catch, however, may be readily released when desired to permit withdrawal of the follower 5 for the operation of loading staples into the machine, by merely first pressing inwardly on the upright wall 18 with the thumb or finger to shift it inwardly sufficiently to remove the bar 27 from the hook 21, and then lifting the end 25 of the catch 22. This will permit withdrawal of the block 17 and the rod 14 with the follower 5 to permit the loading of a new strip of staples on the bar 3. After loading the staple strip the follower 5 may again be placed on the bar 3 and the end block 17 merely forced into position, the forward end of the portion 19 acting on the inclined wall 28 to lift the catch as the block is moved inwardly, the catch being returned to the holding position by the spring 24.

The follower 5 is provided with a downwardly extending lug 29 from its top wall adjacent its forward end to engage a cross wall 30 filling the forward end of the U-shaped bar 3 to prevent the forward end of the follower being shifted to a position under the staple driver when the last staple has been driven.

The handle may be enclosed by suitable check plates 31 to form a convenient and comfortable grip, and these plates may be shaped accordingly. There are preferably two of these plates mounted on opposite sides of the housing bar 9 and secured by any suitable means. They are preferably made of some light material, such, for example, as wood, plastic, aluminum or aluminum alloys, or other suitable light weight material.

The staple driving mechanism is mounted at the forward end of the handle, and particularly on the forward end of the longitudinal housing bar 9. For this purpose the forward ends of the sides 10 of this bar are extended upwardly, as shown at 32, to provide spaced side members to enclose and guide the carrier 33 for the staple driver 34. This carrier, as shown in Figs. 3 and 16, is a substantially U-shaped member with upright spaced side walls 35, and end or connecting wall 36, carrying an upright toothed rack 37. At their forward edges the sides 35 are provided with lugs 38 seating in notches 39 in the side edges of the driver 34. This driver is preferably a flat strip of steel, and is held in position, with the notches 39 embracing the lugs 38 on the carrier, by suitable guide means. That is, the opposite edges of this driver are guided between the upright side portions 32 of the housing, and the forward edges of an intermediate support 40 carrying a small gear 41 mounted on a transverse pin 41a and meshing with the rack 37 on the carrier 33. This support 40 is substantially U-shape and is mounted between the side walls 35 of the driver carrier 33, as shown in Fig. 3, its lower end 42 resting on the transverse bottom wall of the bar 8 at the forward end thereof.

Also guided between the side walls 32 of the housing at the forward edges thereof is a slideable striker 43. This member, as shown in Figs. 11 to 13, comprises an upright flat bar portion 44 carrying on its inner side at its upper end a rack 45 meshing with the gear 41 at the opposite side from the rack 37, as shown in Figs. 1 and 2, and at its lower end is provided with a substantially U-shaped striking head 46, with side walls or legs 47 embracing the opposite sides of the forward end of the side walls 10 of the housing bar 9. At the inner sides of these legs 47 the connecting or end wall 48 is provided with vertical grooves 49 to receive the stepped forward edges 50 of the side walls 10 and provide a stop shoulder 51 adapted to engage the top wall 52 of the striker head 46 to limit upward movement of this striker member. These grooves 49 guide the striker member 43 in its reciprocating movements on the forward edges of the side walls 10 and prevent its lower end being forced laterally out of position by the blow against an object to be stapled.

These elements, including the housing walls 32, are enclosed in a head or casing 53, which is closed at its top by the top wall 54, but open at its lower end and secured over the upright housing walls 32 by any suitable means, such as a transverse pin or rivet 55. The rear wall 56 of this head forms a guide for the carrier 33 for the staple driver, and its front wall 57 forms a guide for the striker member 43. This front wall is provided with a vertical groove 58 in which is a coil spring 59 resting at its lower end on a lug 60 on the front wall of the member 43, and resting at its upper end against the wall 54. There is preferably a pin 61 mounted in this top wall 54 and extended downwardly therefrom which is embraced by this spring to hold it in its proper position. The staple driver 34 is mounted and guided for its vertical sliding movement at its opposite edges between the side walls 32 of the housing, and between the forward edges 65 of the sides of the gear carrying support 40 and the rear face of the striker elements 43. This element 43 is guided for up and down sliding movement at its opposite edges between the housing walls 32, the driver 34 and the inner surface 70 of the forward wall 57 of the head or casing 53.

The driver carrier 33 is guided for vertical sliding movement on the inner sides of the housing walls 32 and between them and the side walls of the member 40, and also between the inner edges of these side walls and the inner surface of the rear wall 56 of the head or casing 53.

As will be seen from Fig. 1, the normal position of the carrier 33 is elevated so that its top is at the underside of the top wall 54 of the head or casing 53, thus holding the staple driver 34 in its upper or retracted position with its lower driving end 62 just above the forward staple 4a, which has been advanced to this position by the staple feed mechanism. The inner surface 63 of the striker element 43 is spaced from the outer end 3a of the staple guide bar 3 a distance substantially equal to or slightly more than the width of the staple prongs and the thickness of the driver 34 to provide a guide or raceway between the bar 3 and the striker 43 for movement of the staple and the driver during the staple driving operation. It will also be seen from Fig. 1 that in the normal position the striker element 43 is in its lower position with the striker head portion 46 extended below the lower wall 25 of the housing 9.

In driving a staple, the operator grips the handle 1, the same as he would any hammer, and swings the free end carrying the head 53 and the other elements to strike the lower end 64 of the striking element 43 against the work (indicated, for example, at 66) to be stapled at the point he wishes to drive the staple. As this lower end hits the surface of the work its downward movement is of course arrested, while the head 53 and the other elements continue their downward movement until the lower surface of the bar 9 hits the surface of the work. This forces the striking element 43 upwardly into the head 53 to the position shown in Fig. 2, carrying with it the rack 45. This movement of the striking element and the rack 45 operating through the gear 41 shifts the rack 37 downwardly and with it the carrier 33, which of course carries with it the staple driver 34 which is connected to this carrier. This forces the lower end 62 of the driver downwardly to the position of Fig. 2 at the lower edge of the housing 9, carrying with it the forward staple 4a and driving the prongs of the staple into the work. As soon as the device is raised from the work the spring 59 forces the striker element 43 downwardly to the position of Fig. 1, which operates through the rack 45, pinion 44 and rack 37 to raise the carrier 33 and the staple driver 34 again to their upper positions, as shown in Fig. 1, ready for the next staple driving operation. As they reach this position, the staple strip 4 is fed forwardly by the follower 5 to position the next forward staple in the raceway under the lower end of the driver 34 for the next driving operation. It will be seen the staple is driven through the lower portion of striking element 43 and therefore the location of the point where the staple is driven is the point at which the lower end of the striker hits or contacts the surface of the work. The operator can, therefore, accurately drive the staple at any location desired by merely striking this location with the lower end of the striker.

The driver 34 is provided in its upper portion with a longitudinal slot 65 for passage of the rack 45 of the striking element 43.

It will be seen from this device and its operation that the operation of the driver to drive

the staple is dependent primarily on shifting of the striking element 43 by the striking blow of its lower end against the work, rather than by the momentum of a weight or hammer element connected to the driver, as is common in prior devices. This greatly simplifies the construction and permits the use of much lighter weight elements. In fact, the whole device itself is of much lighter weight and smaller, and can be used more in the manner of an ordinary hammer and is no more fatiguing in continued use than is such a hammer. The top wall 54 of the enclosing head 53 may be flat, and by reversing, the device is usable as a hammer to complete the driving of a staple should it for any reason not be completely driven by use of the device in the regular manner.

Having thus set forth the nature of my invention, what I claim is:

1. A staple driving machine of the character described comprising a handle, a head structure at one end of the handle including a casing secured to the handle and a vertically slideable striking element mounted within and at the front of the casing, said element projecting at its lower end below the handle providing a guide for a staple, a reciprocable carrier also mounted in the casing, a staple driver in the casing at the inner side of the striking element connected with the carrier, a driving connection within the casing between the striking element and the carrier operable by upward movement of the striker as a result of a blow against an object to shift the carrier and driver downwardly to drive a staple through said guide, and means for feeding staples to the driving position.

2. A staple driving machine of the character described comprising a handle, a head structure at one end of the handle including an upright hollow casing secured to the handle and a vertically slideable striking element mounted within the casing at the inner side of its forward wall, said element projecting at its lower end below the handle and providing a guide for a staple, a reciprocable carrier guided for up and down movement in the casing, a staple driver at the inner side of the striking element connected with the carrier, a driving connection within the casing from the striking element to the carrier comprising a gear between them, toothed racks on the striker and carrier meshing with said gear, a spring tending to hold the striking element in its lower position, and means for feeding staples to driving position under the driver.

3. A staple driving machine of the character described comprising a handle, a head structure at one end of the handle comprising a support including spaced upright side members, a gear mounted between said members, a carrier mounted for up and down sliding movement at the rear edges of said members and including side members extending forwardly at the outer sides of the first members, a toothed rack on the carrier meshing with the gear, a staple driver secured to the side members of the carrier at the forward edges thereof, a striking element mounted for up and down movements at the forward side of the driver and extending at its lower end to a striking position below the handle, a toothed rack on the striking element meshing with the gear on the opposite side from the first rack, a spring tending to shift the striking element to its lower position and the driver to its elevated position, means forming a guideway for a staple to be

driven under the driver, and means for feeding staples to driving position in said guideway.

4. A staple driving machine comprising a handle, a striking head structure at one end comprising an upright support, a gear mounted in the support, a staple driver mounted for up and down sliding movement at the front of said support, a carrier for the driver mounted for up and down movement and including a portion located at the rear of the support, a toothed rack in the carrier meshing with the gear, a striking element mounted for up and down movement at one side of the driver and projecting at its lower end below the handle forming a guideway under the driver for the staple being driven, a toothed rack on the striking element meshing with the gear on the opposite side from the first rack, and means for feeding staples to the guideway.

5. A staple driving machine comprising a handle, a staple guide bar mounted in and extending longitudinally of the handle, means for feeding staples along the bar to the forward end thereof, a striking head structure at the forward end of the handle comprising an upright hollow casing secured to the handle, a striking element mounted in the casing for up and down movement at the forward end of the bar and providing therewith a guideway for a staple being driven, said element extending at its lower end below the bar in striking position, a staple driver mounted to slide in said guideway to drive a staple, a carrier for the driver mounted in the casing, a gear in the casing between the striking element and carrier, and a toothed rack on each of the striking element and the carrier respectively and meshing with the gear on opposite sides thereof to shift the carrier and driver to drive a staple by upward movement of the striker by a blow on its lower end against an object.

6. A staple driving machine comprising a handle, a striking head structure at one end including a casing secured to the handle, a staple guide bar, an upright striking element slidably mounted in the casing and forming a guideway with the front end of said bar for a staple being driven, a driver mounted for upright sliding movement in said guideway, a slideable carrier mounted in the casing, means mounting the driver on the carrier, a gear in the casing between the striking element and the carrier, a toothed rack on each of the striking element and carrier respectively and meshing with the gear on opposite sides thereof to operate the driver by upward movement of said element, a spring in the casing tending to shift said element to its lower position and retract the driver, the lower end of said striking element extending to striking position below the bar and providing a guide for the staple, and means for feeding staples along the bar to the guideway.

7. A staple driving machine comprising a handle, including a guide bar, a striking head structure at one end including a casing secured to the bar, an upright support including spaced side members mounted, in the casing, a gear in said support, a substantially U-shaped carrier slideable at the rear of said support and arranged with its side arms extending forwardly at the sides of said support, a staple driver at the forward side of said support mounted on the side arms of the carrier, a toothed rack on the rear wall of the carrier meshing with the gear, an upright striking element slidably mounted at the forward side of the driver and provided with a toothed rack meshing with the forward side of the gear, a spring in the casing tending to force the striking element downwardly and retract the driver, said striking element including a lower striking end provided with upright side flanges projecting to striking position below the bar and providing with the end of the bar a guideway under the driver for a staple being driven, and means for feeding staples to the guideway.

8. A staple driving machine of the character described comprising a handle, a head structure at one end of the handle including a casing secured to the handle and a vertically slideable striking element mounted within the casing, said element projecting at its lower end below the handle providing a guide for a staple, a reciprocable carrier also mounted in the casing, a staple driver mounted in the casing at one side of the striking element to slide in said guide and connected with the carrier, a driving connection within the casing between the striking element and the carrier operable by upward movement of the striker as a result of a blow against an object to shift the carrier and driver downwardly to drive a staple through said guide, and means for feeding staples to the driving position.
